Patented Nov. 7, 1916.

UNITED STATES PATENT OFFICE.

GEORGE J. DEHN, OF CHICAGO, ILLINOIS.

PIPE-FITTING.

1,203,989.

Specification of Letters Patent.

Patented Nov. 7, 1916.

Application filed December 19, 1913. Serial No. 807,648.

To all whom it may concern:

Be it known that I, GEORGE J. DEHN, a resident of Chicago, in the county of Cook and State of Illinois, have invented certain new and useful Improvements in Pipe-Fittings, of which the following is a full, clear, and exact description.

The invention relates to pipe fittings.

In practice, it has been found to be desirable to connect the drain pipes from the water-closet, lavatory and bath-tub to a common stack, and that it is desirable to connect the drain-pipes for the lavatory and bath tub to the stack below the point where 15 the drain from the closet discharges into the stack, so that the drain from the closet will flush the discharge openings from lavatory, and bath-tub and carry off foreign matter, such as lint, dirt, string and 20 matches. In many instances, horizontal runs of pipe are necessary between the stack and the closet, lavatory and the bath-tub, respectively, and it is desirable to confine these pipes between the joists in the floors, 25 so that they will not protrude and render an offset in the ceiling unnecessary to house them.

The present invention designs to provide an improved T-fitting in which the inlet 30 openings of the stack-pipe are horizontally alined to permit the horizontal runs of pipe to be disposed side by side between the floor and in which provision is made for discharging the drain from the bath-tub or lavatory into the stack-pipe below the point where the drain from the closet is discharged into the stack.

The invention further consists in the several novel features hereinafter set forth and 40 more particularly defined by claim at the conclusion hereof.

In the drawings: Figure 1 is an end elevation of the fitting. Fig. 2 is a side elevation thereof. Fig. 3 is a top plan view of the fitting. Fig. 4 is a section taken on line 45 4-4 of Fig. 1. Fig. 5 is a section taken on line 5-5 of Fig. 4.

The fitting 9 is cast in one piece and comprises a main pipe 10, which is connected 50 to the stack in the drainage system at its ends 11 and 12 and forms a part thereof, and inlet pipes 13, 14 and 15. Inlet pipe

13 leads and discharges the drain into the main 10 at 16 and is adapted to be connected at 17 to the drain-pipe from the water closet, 55 as well understood in the art.

Inlet pipes 14 and 15 are situated at either side of the inlet 13 and lead inwardly and downwardly into the side of the main 10 at the side of and below the inlet 13. 60 Inlet pipe 14 is adapted, at 20, to be connected to a pipe from the lavatory and leads inwardly and downwardly, discharging into the main pipe 10 of the stack, at 18. Inlet pipe 15 is adapted to be connected at 21 65 to a drain-pipe from the bath-tub and is curved downwardly and inwardly to discharge into the main-pipe 10 at 19.

The inlet terminals 17, 20 and 21 of the inlet pipes are horizontally alined, so that 70 the drain-pipes leading to the stack may be readily disposed between the joists and between the floor and ceiling, and the discharge openings of these inlet pipes are relatively disposed so that the solid matter, 75 discharging at 16, from the inlet pipe 13 will pass down and carry away any accumulation of foreign matter which is in the discharge openings 18 and 19 of the inlet pipes 14 and 15. By disposing the discharge 80 openings 18 and 19 below the discharge opening 16, the passages in pipes 14 and 15 are gradually curved to direct the drainage downwardly and longitudinally of the stack instead of discharging it directly against 85 the wall thereof.

The invention thus exemplifies an improved one-piece T-fitting which includes connections for pipes disposed side by side and in which the passages are directed to 90 effectively prevent clogging.

The invention is not to be understood as restricted to the details set forth, since these may be modified within the scope of the appended claim, without departing from 95 the spirit and scope of the invention.

Having thus described the invention, what I claim as new and desire to secure by Letters Patent, is:

A one-piece T-fitting for a drainage system, comprising a stack pipe, a large inlet pipe adapted for connection to a closet and leading into the stack and a plurality of smaller inlet pipes adapted for connection 100

2
to a sink and a bath-tub, the inlet terminals of all of said inlet pipes having their axes in the same horizontal plane and having intersecting portions forming common division walls between them and extended in the same direction for connection to parallel drain pipes disposed laterally of one

another, to permit them to be disposed between two ordinarily spaced joists without cutting away the joists.

GEORGE J. DEHN.
